UNITED STATES PATENT OFFICE.

JHOICHI OMAYE, OF SEATTLE, WASHINGTON.

STOPPER-EXTRACTOR.

1,146,649.

Specification of Letters Patent. Patented July 13, 1915.

Application filed October 19, 1914. Serial No. 867,505.

To all whom it may concern:

Be it known that I, JHOICHI OMAYE, a subject of the Emperor of Japan, residing at Seattle, in the county of King and State of Washington, have invented certain new and useful Improvements in Stopper-Extractors; and I do hereby declare the following to be a full, clear, and exact description of the invention, such as will enable others skilled in the art to which it appertains to make and use the same.

This invention relates to kitchen and table articles, and more especially to stopper extractors; and the object of the same is to produce an article of this kind whose point may be forced through a stopper or cork which has been driven clear into the bottle mouth, and then automatically turned and moved upward by a continued movement of the hand lever.

This and other objects are carried out by constructing the device in the manner hereinafter more fully described and claimed, and as shown in the drawings wherein—

Figure 1 is an edge view of this device partly in section, showing the point as having been passed through the cork, and Fig. 2 is a side view partly broken away and showing the position of parts when the hand lever is given its first or initial movement. Figs. 3 and 4 are side and edge views respectively of the lower end of the device on a larger scale; and Fig. 5 is an enlarged detail of the jaws and the pivot opposite thereto as referred to below.

The framework of this article comprises a bell D having a flaring mouth at its lower end, preferably split into arms f between which the bottle neck G and cork K may be seen, the body of the bell having a hole y through it; and an upstanding forked or bifurcated standard composed of arms B, B standing parallel with and spaced from each other and having claws L at their upper ends. Between the arms is loosely mounted a hand lever J by means of a pivot pin W passing through the arms and through the lever between the extremities of the latter, and the upper end of said lever carries a handle A secured across the lever at a point where it may rest within the claws L. To the lower end of the lever at w is pivoted a link F, and the lower end of the link in turn is pivoted at n to the upper end of a rod P which extends downward through the hole y and occupies about half of the latter.

Alongside this rod P stands a similar rod H extending also downward through the hole y and filling out the latter, so that said hole guides the two rods in their vertical movement. The upper end of the rod H has an outstanding jaw m' provided with a flat upper face, and the lower end of the link F has a similar but reversed jaw m provided with a flat lower face standing parallel with the axis of the pivot n but at one side thereof as best seen in Fig. 1.

The lower ends of the rods P and H are rounded, and preferably provided with reduced tongues s as best seen in Fig. 4. The letter T designates a point member or foot which is formed of substantially the configuration shown in Figs. 3 and 4 and has a reduced and pointed toe p at its lower end and a reduced heel x at its upper end adapted to lie against the rounded lower extremity of the rod H when the parts stand as seen in Fig. 3. The upper side of this toe is recessed as seen in Fig. 4 to admit the tongues s, that at the lower end of the rod P being pivoted to the toe as at i', and that at the lower end of the rod H having a cross pin i movable in a slot t which is formed in the upper portion of the toe T. This slot as shown extends transversely through the toe, and it extends on a line radial to the pivot i' as best seen in Fig. 3.

The operation of this device is as follows: The handle A is thrown up into the claws L and the rod H raised so that the toe stands as seen in Figs. 1 and 3. The extractor is then brought into position above the cork K which it is desired to remove, and the point p of the toe T forced downward through the cork until the mouth or arms f of the bell D strike upon the neck G of the bottle, at which time the parts stand as seen in Fig. 1. The lever J is now moved to an oblique position by swinging the handle A out of the claws L to the position shown in Fig. 2. This causes the link F to turn on the pivot n and draw the rod P upward slightly, while the contact of the faces of the jaws m and m' simultaneously forces the rod H downward slightly. The result is that the pivot i' of the toe is moved upward, while the pin i simultaneously moves downward as the slot t permits, and the toe T as a whole is tilted from the full-lined position in Fig. 3 to that shown in dotted lines, the tilting being possible because the toe at this time stands beneath the cork K within the bottle G. The

lever J is now swung still farther around its pivot W, with the result that its short arm and pivot w move upward rather than outward from between the arms B, and the link

5 F is caused to move upward so that the rod P and with it the rod H travel upward. In this movement the upper side of the toe T soon contacts with cork K, and the latter is forcibly drawn from the mouth or bottle

10 neck G.

What is claimed as new is:

1. In a stopper extractor, the combination with a framework, a pair of rods slidably mounted therethrough, and means for moving one rod slightly upward and the other rod slightly downward simultaneously and subsequently moving the first-named rod upward further; of a toe pivoted to the lower end of the first-named rod having its lower extremity pointed, and slideable connections between and its upper end and the second-named rod.

2. In a stopper extractor, the combination with a framework, a pair of rods slidably mounted therethrough, and means for moving one rod slightly upward and the other rod slightly downward simultaneously and subsequently moving the first-named rod further upward; of a toe pivoted to the lower end of the first-named rod and having its lower extremity pointed and its upper portion provided with a transverse slot whose length is radial to said pivot, and a transverse pin on the lower end of the second-named rod loosely mounted in said slot, whereby the toe is rocked on its pivot by the relative movement of said rods, for the purpose set forth.

3. In a stopper extractor, the combination with a pair of rods disposed side by side, a toe pivoted to the lower end of one rod, and a connection between the other rod and toe whereby the latter is turned on its pivot by the relative movement of said rods; of a framework including a bell adapted to embrace the bottle neck and having an upright hole through which said rods are slidably mounted and a standard rising from said bell, a lever pivoted to the standard, a link pivotally connecting said lever with the upper end of the rod to which said toe is piv-

oted, and means on the link for imparting a slight downward movement to the other rod when the lever is turned to raise the first-named rod.

4. In a stopper extractor, the combination with a pair of rods disposed side by side, a toe pivoted to the lower end of one rod, and a connection between the other rod and toe whereby the latter is turned on its pivot by the relative movement of said rods; of a framework including a bell adapted to embrace the bottle neck and having an upright hole through which said rods are slidably mounted and a standard rising from said bell, a lever pivoted to the standard, a link pivotally connecting said lever with the upper end of the rod to which said toe is pivoted, a jaw projecting laterally from said link alongside its pivot, and a second jaw projecting laterally from the second-named rod and adapted to coact with the first-named jaw, for the purpose set forth.

5. In a stopper extractor, the combination with a pair of rods disposed side by side, a toe pivoted to the lower end of one rod, and a connection between the other rod and toe whereby the latter is turned on its pivot by the relative movement of said rods; of a framework including a bell adapted to embrace the bottle neck and having an upright hole through which said rods are slidably mounted and a forked standard rising from said bell and having claws at the upper end of its arms, a lever between said arms and pivoted thereto between its ends, a handle at the upper end of the lever adapted to engage said claws when the lever is parallel with the arms, a link pivotally connecting the lower end of the lever with the upper end of that rod to which the toe is pivoted, and jaws on the link and on the other rod for causing the latter to move downward when the first-named rod is elevated by the movement of the lever, for the purpose set forth.

In testimony whereof I affix my signature in presence of two witnesses.

JHOICHI OMAYE
